The ornamental design for a dog/cat leash coupler, as shown and described.

DESCRIPTION

FIG. 1 is a top perspective view of a dog/cat leash coupler showing my new design, a leash.

FIG. 2 is a top view thereof.

FIG. 3 is a bottom view thereof.

FIG. 4 is a front elevational view thereof.

FIG. 5 is a side elevational view thereof; and,

FIG. 6 is the opposing side elevational view of FIG. 5.

The broken lines in FIG. 1 illustrate environmental subject matter that form no part of the claimed design. It being noted that the lettering and characters are raised above the surface of the coupler.
